ELECTRICAL ELEMENT AND METHOD OF INSULATING SAME

John M. Alden, 380 Grove St., Needham, Mass.

Filed Jan. 21, 1959, Ser. No. 788,100

1 Claim. (Cl. 18—54)

This invention relates to the art of molding electrical insulation around electrical circuit elements such as resistors, terminals and the like, and more particularly to a method of locating such elements in an insulating casing formed by modern high pressure injection molding processes.

It has been common to mold insulation on one or more circuit elements having leads or terminals connected thereto by potting or pouring fluid insulation around the elements held in a pot like receptacle which forms a part of the finished product. Potting is inherently a low pressure process and does not form a strong seal around the elements. Since no closed mold is involved it results in a poorly formed external and bulky appearance. Furthermore, the process requires careful attention of the operator and is slow as a result of the time required for potting and curing.

Injection molding with plastic insulation appears highly preferable because of the better sealing action, much faster injection and curing speed and the smooth, compact appearance of the product. However, high pressures are needed to force the fluid plastic into a mold and around the components, and such high pressures disarrange the elements with respect to each other and the walls of the mold cavity. The result has been that the components are not properly located in the cavity, and an insufficient thickness of insulation is formed around them.

According to the present invention a method of encasing an electrical element in insulation comprises, fitting a separate support in a mold, placing an electrical element on the support to securely position the element in the mold, closing the mold, injecting insulation into the mold at least partially to encase the element, and subsequently separating the encased element and support from the mold.

Preferably the support is formed of a primary covering of a fusible material compatible with a secondary encasing material. The support may be molded on a part of the element prior to secondary encasement, or the primary covering may be formed separately and applied to the element prior to putting it in the mold for secondary encasement.

For the purpose of illustration typical methods are illustrated in the accompanying drawings in which:

FIG. 1 is an end elevation of a mold;

FIG. 2 is a side elevation of one-half the mold;

FIG. 3 is an enlarged fragmentary side elevation of the mold showing a resistor and connector supported therein;

FIG. 4 is a section on line 4—4 of FIG. 3;

FIG. 5 is an elevation like FIG. 3, showing the encased resistor and connector;

FIG. 6 is a section on line 6—6 of FIG. 5;

FIG. 7 is a section on line 7—7 of FIG. 6;

FIG. 8 is a side view of the encased element;

FIG. 9 is a bottom view of the encased element;

FIG. 10 is a side elevation of a primary mold half showing an assembly of resistors, a connector and an insulated wire therein;

FIG. 11 is a side elevation of the assembly partially encased in a support;

FIG. 12 is a side elevation of a secondary mold half with the supported assembly therein;

FIG. 13 is a side view of the assembly insulated by the steps of FIGS. 10 to 12;

FIG. 14 is a section on line 14—14 of FIG. 13;

2

FIG. 15 is a section on line 15—15 of FIG. 12;

FIG. 16 is a left end elevation of a preformed support;

FIG. 17 is a right end elevation of the preformed support;

5 FIG. 18 is a side elevation of the preformed support shown partly in section, and with an assembly resistor, a terminal and insulated wires connected thereto;

FIG. 19 is a side elevation of a mold half with the preformed support and assembly therein;

10 FIG. 20 is a section on line 20—20 of FIG. 19;

FIG. 21 is a side elevation of the encased preformed support and assembly;

FIG. 22 is an end elevation of a two part support;

FIG. 23 is a section on line 23—23 of FIG. 22;

FIG. 24 is a plan view of the two part support;

15 FIG. 25 is a section of a mold half with the two part support holding a connector and lead therein;

FIG. 26 is a side elevation showing the encased two part support and connector; and

20 FIG. 27 is an isometric view of the connector and lead of FIGS. 24 to 26.

In FIGS. 1 to 9 is shown the method of encasing a tube cap connector assembly comprising a clip 1 having jaws 2 and a connector portion 3, a resistor element 6 of one 25 whose leads 4 is soldered to the clip, the other lead being joined to a wire 7 having an insulating sheath 8.

Insulation is applied to the assembly in a mold 11 having two halves 11a and 11b, each of which comprises a cavity with a semicylindrical horizontal chamber 12, vertical chamber 13, and wire passage 14 and entrance 16. The vertical chamber 13 is adapted to receive a cylindrical support plug 17 having an upwardly extending tubular wall 18 within which is located a stub 19. The stub 19 is generally cylindrical, as best shown in FIG. 6, and spaced 35 inwardly of the wall 18, except for two ears 21 which abut the wall, thereby defining two arcuate spaces between the wall and stub.

The plug 17 is adapted to support the tube cap connector 1 with its jaws 2 fitting in the arcuate spaces of the 40 plug and with its connector portion 3 resting on top of the stub 19. In addition to supporting the connector, the stub covers the lower end of its jaws and the underside of the connector portion.

When the connector is fitted on the plug the connector 45 and plug are placed in one mold half with the resistor 6 in the horizontal chamber 12 and the insulated wire extending from the passage 14 into the horizontal chamber 12. When the mold halves are clamped together in a conventional manner, the insulation is gripped in the passage 14, and the resistor is gripped between two pairs of studs 15 whose ends are shaped to extend slightly around the sides and ends of the resistor 6. The insulated wire, resistor and connector are then positively located in the cavity with the tubular walls 18 of the plug 17 sealing off the 55 connector jaws 2.

A hot, fluid, insulating plastic, such as polyethylene, vinyl resins or nylon, is injected through the opening 16 at a high pressure, for example 1200 p.s.i. so as to flow around all exposed parts of the connector assembly and 60 form the jacket 26 of FIGS. 8 and 9. An insulating material compatible with the insulation on the wire 8 will form a homogeneous bond therewith and permanently embed the wire end in the jacket and seal the assembly against moisture, contamination and leakage. The jacketed assembly is removed from the mold together with the plug and are thereafter separated.

The jacket and connector assembly are thereby molded as a unit with a single injection shot. Since the connector assembly is also embedded in the jacket, excellent strain relief is provided for the leads, minimizing wire and solder joint fatigue under vibration and shock. The connector is seated in the jacket, but its jaws are free from acci-

dental coating owing to the sealing off effect of the plug walls 18.

Another way of insulating a connector assembly is shown in FIGS. 10 to 16, wherein the assembly comprises a connector pin 31 having a contact portion 32 and connector portion 33 connected to a series of resistors 6 with leads 4 and an insulated wire 8. The assembly is located in a first mold of which one half 34a is shown in FIG. 10. The first mold comprises a horizontal chamber 36 with opposite end openings 37 and 38, three semi-cylindrical vertical recesses, two horizontal cylindrical recesses 41, and three studs 42 having concave upper surfaces complementary to the resistors 6. When the mold halves are clamped together the resistors are seated on the studs 42.

A first or primary jacket 46 is formed by injecting hot plastic under high pressure as described above. The first jacket has vertical bosses formed by the recesses 39, and horizontal bosses 48 formed by recesses 41. Recesses 49 exposing the resistors 6 are formed by the studs 42 as shown in FIGS. 11, 12 and 15. An annular boss 50 is formed at the enlarged right end of chamber 36.

The first jacket 46 forms a support for the connector-resistor assembly in a second mold of whose halves 51a and 51b are shown in FIG. 12. The second mold has a horizontal chamber 52 with end passages 53 and 54. The contact portion 32 of the pin 31 is held in one end opening 53 with its connector portion 33 extending into the chamber 52. In the second mold 51a-51b the bosses 47, 48 and 50 of the first jacket 46 yieldingly abut the walls of the chamber 52 positively locating the jacket therein. Thus when a matrix molten plastic is forced in the chamber under high pressure, the primary jacket and enclosed connector assembly are held against movement. As shown in FIG. 13 the outer jacket or matrix 56 fuses with the inner jacket 46 and completes the encasing of the connector assembly. The pin 31 is embedded in the matrix, and the openings 49 to the resistors 6 are closed. The bosses 47, 48 and 50 having served their purpose of holding the jacketed assembly in position are merged with the outer jacket.

As shown in FIGS. 17 to 21 the first or primary jacket 61 may be preformed prior to the assembly of elements therein. In FIGS. 16 to 20 the primary jacket is a generally cylindrical body of plastic insulating material formed with lengthwise cylindrical chambers 62, connecting passages 63 between the chambers, and upper and lower bosses 64. One or more resistors 6 and insulated wires 66 are inserted in the chambers 62, and solder connected to a pin jack 67 after their lead wires 68 are passed through a wall 71 at the right end of the primary jacket. The jack 67 is positioned against an axial boss 72.

The primary jacket supports the assembly of wires, resistors and jack in a mold 73 shown in FIGS. 19 and 20, comprising halves 73a and 73b. The halves form a main chamber 74 having upper and lower recesses 76 receiving the bosses 64 of the jacket. A separable mold member is held in a ribbed chamber 78 by attachment to the mold. The inner end of the member has a tip (not shown) over which the jack 67 fits. The boss 72 prevents the jack from slipping off the tip.

With the assembly so supported in the mold a matrix 79 is injected fusing with the insulation of wires 66, and completing the sealing of the resistor jack assembly except for the inside of the jack. The matrix 79 merges with the preformed support as indicated in FIG. 17 thereby forming an integral unit.

In FIGS. 22 to 26 is shown a method of supporting an electrical jack 81, elements in a two-part preformed body 86a, 86b. As shown in FIG. 27, each jack 81 is formed by punch-press techniques from resilient sheet metal and has a triangular socket portion 82 from which a rectangular base 83 extends at one end, and at the other end a lug 84 to which the conductor of an insulated wire 85 is

attached and soldered. The two part body 86a-86b forms entrances 87 for the insulated wires 85, and rectangular recesses 88 for receiving and positioning the rectangular base 83 and solder lug 84. The solder lug 84 extends into a channel 89 laterally communicating with the rectangular recess 88. Between each channel 89 and wire entrance 87 the two-part body forms a wall 91 having a small passage 92 communicating with the recess 89 and a larger passage communicating with the wire entrance 87.

As shown in FIG. 25 the jacks 81 and wires 85 are supported in a two-part mold 96a-96b by clamping the two-part support 86a-86b therein having first fitted the jacks and wires in the two part body. The wires and jacks may be joined prior to placing them in the support. When in the support the insulation of wire 85 fills the enlarged passage 93 closing off the recess 88 and channel 89 from the wire entrance 87 as shown in FIG. 25.

The mold 96a-96b has a main chamber 97 and a smaller chamber 98 which is filled by the two-part support 86a-86b. The wall 91 of the support closes off the smaller chamber 98 from the main chamber 97. Thus when a matrix 99 of hot plastic, under high pressure, is injected in the mold, the support not only holds the clip and wire firmly positioned, but also restricts the matrix to covering the wire 85 and the part of the support to the right of the wall 91, so that the matrix does not reach the jack 81.

From the foregoing description it can be seen that the present method insures that the various circuit elements will be positioned properly in their insulating casing despite the high pressure faces tending to dislocate them in the mold. The injected matrix or casing not only affords rigid support, resistance against breakage from shock and vibration and complete sealing against moisture, dust and electrical leakage, but also it is a far more speedy, inexpensive and convenient operation.

While I have shown several specific methods by which the advantages of injection molding can be fully realized, it should be understood the steps illustrated may be combined in other and equivalent ways within the scope of the appended claim.

I claim:

The method of encasing in insulation an electrical element of relatively large width having a lead of relatively smaller width connected thereto which comprises locating the element in an insulating support having two parts forming a chamber of a size to receive said element and a wall at one end of said chamber having a smaller opening therefrom for said lead, said wall facing toward said element and away from said lead so as to engage the element against movement axially of the lead, placing the insulating support, element and lead in a mold so that the support is engaged by the mold thereby positively to locate the element in the mold, simultaneously clamping in the mold a portion of the lead spaced from the element so that the element and said lead portion are mechanically engaged without further preparation such that the intermediate portion of the lead is positively held against dislocation by pressure of insulation injected in the mold, and injecting an insulating coating over said support.
